CONVERTING PETROLEUM OILS

Application filed July 24, 1931. Serial No. 552,974.

This invention relates to converting petroleum oils; and it comprises a method of utilizing aluminum chlorid in the conversion of high boiling oils into lower boiling oils with a minimizaton of loss as gas and coke and high utilization of the aluminum chlorid, wherein a mixture of liquid high boiling oil and aluminum chlorid is heated to a temperature of about 380° to 420° C. and is maintained at that temperature to allow equilibrium to become established to a substantial degree, vaporization being minimized as far as possible, usually by employing a pump pressure of the order of 2500 pounds during the equilibration; the equilibrated mixture being afterwards distilled to recover the low boiling oils formed; all as more fully hereinafter set forth and as claimed.

In the usual method of making gasoline and kerosene from gas oil and other relatively heavy oils by distilling with aluminum chlorid, the operation is often described as depending on a "disturbed equilibrium".

The term is in a sense misleading since no equilibrium is ever instituted in the whole body of original oil. In hot gas oil, aluminum chlorid produces rearrangement of the hydrocarbon groups resulting in the formation of new lighter oils and heavier oils and this tendency if uninterrupted comes to some sort of equilibrium or balance between the two. By removing the light oils as fast as they are formed, while a tendency to equilibration remains and is utilized, there is at no time any real equilibrium. At any instant, the aluminum chlorid can be regarded as beginning equilibration of a new body of oil, the heavier residue left in the still. In the usual operation, a charge of oil in the still is mixed with aluminum chlorid and progressively distilled. The charge thickens and changes and finally becomes pitch or coke holding the aluminum chlorid. The distillate carries with it some gas, often

largely butane and usually contains a very large proportion of very light constituents. The residue in the still is of no value and is discarded. In this operation insofar as gas and coke are formed there is a waste. So to speak, the division of the original oil into light and heavy products has gone too far each way. The yield of low boiling oils of medium volatility is not as satisfactory as could be desired. Nor is the converting power of the aluminum chlorid utilized to a maximum.

In the stated operation there is no opportunity for any equilibrium to be produced; the whole charge is not maintained in contact with the aluminum chlorid for a sufficient time to accomplish this. What is true of this batch operation is also true of certain proposed continuous methods wherein aluminum chlorid and oil are sent through hot tubes as a flowing current. Vapor forms as before and once formed it has little chance for reaction with the aluminum chlorid, this remaining mainly in the liquid phase. As before, the net result is an overhead distillate of low boiling oil and a residue of pitch or coke. Insofar as this pitch or coke is formed, it represents a loss of material; a loss of oil which has not been transformed into gasoline and kerosene.

In ideal operation, the whole body of oil, without subtraction of any reaction product, would be maintained in contact with the aluminum chlorid at a high temperature until equilibrium is obtained until the converting action of the aluminum chlorid is utilized to a maximum. The new oil produced would have widely different distilling characteristics. In approaching this ideal, it is noted there is very little formation of coke or gas; the liquid does not thicken up with the production of pitch and coke as is the case in the ordinary "disturbed equilibrium" methods.

These facts are utilized in the present in-

vention. We have found that better results as regards utilization of aluminum chlorid, conversion of oil and minimization of the wasteful formation of gas and coke result by maintaining, as far as is practical, the whole body of oil in liquid form in contact with the aluminum chlorid for a reasonable time; a time which is of the order of 6 to 15 minutes. The temperature of equilibration is advantageously around 380° to 420° C. In order to maintain the oil, as far as possible, in the liquid form at this temperature we use a pressure of the order of 2500 pounds. The pressure may drop to 1000 pounds or go to 3000, but on the whole around 2500 pounds represents the best economic balance. Pressure by gases from an outside source or autogenerated pressure from the system itself may be used, but it is better for the present purposes to rely on pump pressure and arrange heating conditions so as to minimize production of vapor as far as possible. The reaction mixture may, for example, be contained in an autoclave without much vapor space or it may flow through a system of hot tubing at such a rate and for such a period of flow as will enable heating the oil in the system at the described temperature for at least 6 minutes; that is so that every portion of the mixture will have at least 6 minutes heating. A heating time of 15 minutes is better. With a tubular heating system, a flooding feed should be used; i. e. the tube should be kept as full of liquid as possible.

Under the conditions stated, there is but little formation of coke. The magma of oil and aluminum chlorid introduced into the tubes flows through without forfeiting its liquidity until the pressure is released beyond the tubes and distillation takes place. This retention of liquidity depends on allowing no substantial formation of vapor and gas. If much vapor formation be permitted, coke will form and will tend to plug the tubes.

In the foregoing description we have had in mind more particularly high temperatures of the order of 400° C. with correspondingly quick action. At these high temperatures high pressure is necessary to restrain production of vapor. The heating time at these temperatures is, as stated, about 6 to 15 minutes. By slower operation, affording more time for reaction, much lower temperatures may be employed.

As illustrating the results obtained under different conditions, a 36° Bé. solar oil from a mid continent crude with an admixture of 3 per cent anhydrous aluminum chlorid gave a yield of about 37.5 per cent of marketable gasoline on heating for 15 minutes at 2500 pounds pump pressure and at 400° C., under conditions permitting little formation of vapor. Under the same conditions with the

same amount of aluminum chlorid, the same solar oil heated for 15 minutes at 380° C. gave 36 per cent gasoline. The pressure used was somewhat higher, being about 3000 pounds. On the other hand, with less aluminum chlorid and less time at a somewhat higher temperature, a somewhat greater yield of gasoline was obtained. The time was 10 minutes, the temperature 410° C. and the pressure 2400 pounds, with a yield of 42 per cent gasoline.

In the accompanying illustration we have shown, more or less diagrammatically, certain apparatus within the purview of our invention and susceptible of use in performing the described process.

In this showing the drawing is a view in vertical section.

Describing the elements in the order of their use, element 1 is a pump of any suitable type taking oil from inlet 2 and delivering it through coil 3 within a heating housing 4. The pump is of such a type as is adapted to deliver oil at the outlet of the apparatus at a pressure of between 1000 and 3000 pounds. Passing upward through the heating coil hot oil passes through conduit 5 where it is joined by aluminum chlorid introduced through inlet 6. It is convenient to introduce the aluminum chlorid as a pumpable magma of heavy oil and aluminum chlorid. Pumping means, not shown, are used in this event. The hot mixture of oil and aluminum chlorid which may contain aluminum chlorid in about the proportion of 2 to 3 per cent passes through heating coil 7 in furnace housing 8 past relief valve 9 to a flash chamber 10. This may be of any suitable type for promoting disengagement of vapors.

Advantageously, the top portion 11 is arranged with shelves or packing devices. As shown, the lower portion of the tower 12 is unobstructed and is provided with drainage means 13 valved at 14. Vapors formed in the tower pass through conduit 15 to condenser 16. The liquid withdrawn at 14 is a fairly fluid mixture of aluminum chlorid and oil. But little coke is formed in the present operation. This mixture may be submitted to distillation to obtain a further proportion of gasoline and kerosene or it may be otherwise utilized.

What we claim is:

1. In the conversion of high boiling oils to low boiling oils with the aid of aluminum chlorid the process which comprises making a mixture of aluminum chlorid and oil, the amount of aluminum chlorid being of the order of 2 to 3 per cent and heating such mixture in liquid phase to a temperature around 400° C. in the absence of added hydrogen, heating being for a period ranging from 6 to 15 minutes and under a pressure adapted to restrain to a minimum the formation of vapor, this pressure being generally between

1000 and 3000 pounds; and thereafter distilling the treated mixture.

2. In the conversion of high boiling oils to low boiling oils the process which comprises heating a mixture of heavy oil in liquid phase with 2 to 3 per cent aluminum chlorid in the absence of added hydrogen to a temperature of about 400° C. under a pressure of about 2500 pounds, heating being for 10 a period of at least 6 minutes.

3. In the conversion of high boiling oils to low boiling oils the process which comprises heating a mixture of heavy oil in liquid phase with 2 to 3 per cent aluminum chlorid in the absence of added hydrogen to 15 a temperature ranging from about 380° to 420° C. until equilibrium is substantially attained, products of reaction being kept in the oil body as nearly as possible and the whole 20 operation being conducted under sufficient pressure and with conditions restraining substantial formation of vapor; and thereafter distilling the reacting mixture to obtain low boiling oils.

25 4. In the conversion of high boiling oils to low boiling oils with the aid of aluminum chlorid, the process which comprises making a mixture of aluminum chlorid and oil, the amount of aluminum chlorid being of the 30 order of 2 to 3 per cent and heating such mixture in liquid phase to a temperature around 400° C., in the absence of added hydrogen, heating being for a period ranging from 6 to 15 minutes and under a pressure adapted 35 to restrain to a minimum the formation of vapor, this pressure being generally between 1000 and 3000 pounds; and thereafter distilling the treated mixture without at any time during the process subjecting the material 40 treated to temperatures substantially above 420° C.

45 5. In the conversion of high boiling oils to low boiling oils the process which comprises heating a mixture of heavy oil in liquid phase with 2 to 3 per cent aluminum chlorid in the absence of added hydrogen to a temperature of about 400° C. under a pressure of about 2500 pounds, heating being for 50 a period of at least 6 minutes; the said process being conducted without at any time during the process subjecting the material treated to temperatures substantially above 420° C.

55 6. In the conversion of high boiling oils to low boiling oils the process which comprises heating a mixture of heavy oil in liquid phase with 2 to 3 per cent aluminum chlorid in the absence of added hydrogen to a temperature ranging from about 380° to 60 420° C. until equilibrium is substantially attained, products of reaction being kept in the oil body as nearly as possible and the whole operation being conducted under sufficient pressure and with conditions restraining substantial formation of vapor; and thereafter

distilling the reacting mixture to obtain low boiling oils without at any time during the process subjecting the material treated to temperatures substantially above 420° C.

In testimony whereof we have hereunto affixed our signatures.
